DESIGN FOR A CHAIN

Maurice Anderson, Edgewood, R. I.

Application May 1, 1940, Serial No. 92,076

Term of patent 7 years

To all whom it may concern:

Be it known that I, Maurice Anderson, a citizen of the United States of America, residing at Edgewood, county of Providence, State of Rhode Island, have invented a new, original, and ornamental Design for a Chain, of which the following is a specification, reference being had to the accompanying drawing, forming a part thereof.

Fig. 1 is a top plan view of a chain showing my new design;

Fig. 2 is a bottom plan view;
Fig. 3 is an end view; and
Fig. 4 is a perspective view of one of the links thereof.

I claim:

The ornamental design for a chain, substantially as shown.

MAURICE ANDERSON.
